ESCAPEMENT MECHANISM

Harold J. Graham, Highland Park, and Paul F. Powder, Detroit, Mich., assignors to Graham Manufacturing Corporation, Detroit, Mich., a corporation of Michigan

Application December 15, 1949, Serial No. 133,162

3 Claims. (Cl. 10—162)

1

This invention relates to escapement mechanism and more particularly to the type of escapement used to deliver or transfer studs, screws, pins or similarly shaped machine elements from a storage magazine.

Objects of this invention are to provide an escapement mechanism which will successively deliver studs or other pieces from a magazine as they are required by a welder or other apparatus, which is simple in construction, which is rapid and automatic in operation, which is not subject to jamming, which is adaptable to mass production techniques, which is operable by compressed air or other working fluid, which is economical to manufacture and which improves the art generally.

In a broad aspect the invention contemplates an escapement for feeding one stud or other piece at a time from a magazine or other storage place, which escapement comprises a body having a passageway therein acting as a path along which the studs proceed in stacked relationship from the magazine. The passageway is normally blocked by a centrally positioned finger so that the stack of studs is restrained from further movement. Two flanking fingers are disposed along the passageway on either side of the central finger at respective distances greater than the longitudinal length of one of the studs. Means are provided for moving the fingers so that the stack is restrained by one of the flanking fingers as the bottom-most stud is transferred from the central finger to the other flanking finger, the subsequent return of the fingers to their normal positions releasing the bottom-most stud so that it is delivered to the welding gun or other apparatus.

In another aspect the body is provided with three cylindrical cavities whose respective axes intersect the axis of the passageway for the studs. Each cavity has reciprocatingly arranged therein a piston or plunger carrying a finger. The centrally arranged plunger is biased so that its finger normally blocks the passageway thereby to restrain the studs from continuing through such passageway. The outer cavities are positioned on either side of the central cavity so that the flanking fingers are disposed along the passageway on either side of the central finger at respective distances greater than the longitudinal length of an individual stud. The fingers are moved by a working fluid which may be either hydraulic or pneumatic, introduced behind the plungers so that the corresponding fingers are moved to transfer the studs.

2

In a specific aspect compressed air from an external air supply is introduced into one end of a passage arranged in the body so that its opposite end terminates in the central cavity thereby moving the control finger against the force of a spring to drop the stack. Further air passages are provided in the body which interconnect the respective outer cavities with the central cavity. These latter passages are positioned so that air is introduced from the central cavity to the outer cavities whereby the outer fingers are moved against the forces exerted by correlated springs after the transfer of the central plunger from the passageway blocking position. The movement of one of the flanking fingers brings the end thereof into contact with the next-to-the-bottom stud thereby restraining such stud and the studs stacked thereabove. The other flanking finger is moved to block the passageway to restrain the bottom-most stud released previously by the retraction of the central finger. Subsequent disconnecting of the air supply permits the springs to return the correlated fingers to their normal positions thereby dropping the stack until it is again restrained by the central finger and simultaneously releasing the bottom-most stud held by the second flanking finger.

These and further objects, aspects and advantages of the invention will be apparent from the following detailed description and by reference to the accompanying drawings wherein.

Fig. 1 is an end view of the escapement;

Fig. 2 is a sectional view on the line 2—2 of Fig. 1 showing the fingers in their normal positions; and

Fig. 3 is a sectional view on the line 2—2 of Fig. 1 showing the fingers in their transferred positions.

Referring to the drawings, the escapement 26 comprises a body 90 wherein is provided an aperture such as the passageway 92 into the top of which the studs S are introduced from a magazine (not shown), for example by a conduit 28. The travel of the studs along the passage 92 is normally blocked, as in Fig. 2, by a tip of a finger 94 which is reciprocatingly disposed in an aperture having an axis disposed perpendicularly to the axis of the passageway 92. To prevent rapid wear, the tip is preferably of tungsten carbide or other abrasive-resistant material silver soldered to the end of the finger 94.

The finger 94 is biased in its passage-blocking position by a spring 96, one end of which seats 55 upon a piston 98 attached to one end of the

finger, the finger being pressed into an aperture through the piston. The opposite end of the spring 98 seats in a recess in a head 100 which is attached to the side of the body 90 by the bolts 99. Arranged on either side of the centrally positioned finger 94 at a distance therefrom greater than the overall axial length of an individual stud S are two flanking fingers 102 and 103 respectively. With the exception of their axial length these fingers 102 and 103 are similar to each other in construction, each having a tungsten carbide tip at one end and a skirted piston 104 attached to the other end thereof. Springs 107 are arranged circumjacent the fingers 102 and 103 respectively between the correlated pistons 104 and the end of the cylinder apertures in the body 90 wherein the respective pistons 104 are disposed thereby to bias the fingers so that the tips thereof are normally withdrawn from the passageway 92.

The finger 94 is moved out of the path of the studs S against the restoring force exerted by the spring 96 by means of compressed air or other working fluid introduced through a conduit 106 (Fig. 2) in the side of the body 90 and thence through a passage into the cylinder aperture at the finger end of the piston 98. After the piston 98 has moved a sufficient distance to uncover passages such as the ports 108, air is introduced behind the pistons 104 so that the corresponding fingers 102 and 103 are moved into the passageway 92, as is shown in Fig. 3.

The conduit 106 is connected to a supply of compressed air through a conventional two-way control valve (not shown) one position of which connects the conduit to the air supply, the other valve position bleeding the conduit to atmosphere. The control valve may be actuated either mechanically, pneumatically or electrically, depending upon the means of operation of the apparatus associated therewith. For example, when the escapement is used to feed studs to a welding gun the valve actuating mechanism is arranged to complete one operating cycle of the valve during each welding cycle.

As described heretofore, the studs S are fed from the magazine through the conduit 28 with random axial orientation. The studs S proceed along the conduit 28 under the force of gravity, aided, if necessary, by a stream of compressed air (not shown) thence through the passageway 92 until their forward progress is blocked by the finger 94. The connecting of the conduit 106 to the compressed air supply by the control valve, as described above, retracts the finger 94 so that the stack of studs S, is permitted to travel further along the passageway 92. When the finger 94 has been retracted sufficiently so that the piston 98 uncovers the ports 108, the fingers 102 and 103 are moved into the passageway 92 so that the next-to-the-bottom stud is forced against the passageway wall by the finger 102, thereby restraining further movement of the stack; the finger 103 simultaneously blocking the passageway to stop the bottom stud which has dropped to the position shown in Fig. 3.

The subsequent venting of the conduit 106 at atmosphere by the control valve permits the spring 96 to return the finger 94 so that it again blocks the passageway 92. The conjoint movement of the piston 98 bleeds the cylinders of the pistons 104 to atmosphere through the ports 108 and a vent 120 so that the springs 107 retract the fingers 102 and 103. The retraction of finger 102 releases the stack of studs so that it drops

until again restrained by the finger 94. The simultaneous retraction of the finger 103 releases the bottom stud so that it drops into a conduit 114 leading to the chuck of a welding gun or other apparatus (not shown).

It should be understood that the present disclosure is for the purpose of illustration only and that this invention includes all modifications and equivalents which fall within the scope of the appended claims.

We claim:

1. A pneumatically operated escapement for feeding one stud at a time from a magazine, comprising a body having a passageway therein forming a path along which the studs proceed in stacked relationship from the magazine, said body also having three cylindrical cavities therein whose respective axes intersect the axis of the passageway, a plunger having a finger associated therewith reciprocatingly disposed in each of the respective cavities, a spring biasing the centrally positioned finger so that it normally blocks the passageway thereby to restrain the studs, the two outer cavities being positioned so that the two flanking fingers spaced along the passageway on either side of the central finger at respective distances greater than the longitudinal length of one of the studs, springs biasing the two flanking fingers respectively so that they are normally held clear of the passageway, said body having a plurality of air passages therein, the ends of the first of said passages connecting respectively with an air supply and the central cavity so that the central finger and associated plunger can be moved against the force exerted by the correlated biasing spring to release the bottom-most stud, the other air passages interconnecting the respective outer cavities with the central cavity whereby the movement of the central plunger from the passageway blocking position permits air to flow through such passages to the outer cavities thereby to move the flanking plungers so that the stack is restrained by one of the flanking fingers as the bottom-most stud is transferred from the central finger to the other flanking finger, the subsequent disconnecting of the air supply permitting the springs to return the fingers to their normal positions releasing the bottom-most stud.
2. A fluid operated escapement for feeding one stud at a time from a magazine, comprising a body having a passageway therein forming a path along which the studs proceed in stacked relationship from the magazine, said body also having three cylindrical cavities therein whose respective axes intersect the axis of the passageway, three plungers each having a correlated finger associated therewith reciprocatingly disposed in the respective cavities, a spring biasing the centrally positioned finger in a normal position blocking the passageway thereby to restrain the stack of studs, the two outer cavities being located to position the two flanking fingers along the passageway on either side of the central finger at respective distances greater than the longitudinal length of one of the studs, said flanking fingers being movable from normal retracted positions wherein the passageway is unobstructed to blocking positions wherein the fingers enter the passageway, fluid means for retracting the centrally positioned plunger so that the associated finger releases the stack, said means subsequently moving the other plungers so that the associated flanking fingers move into their blocking positions wherein the stack is restrained by

one of the flanking fingers as the bottom-most stud is transferred from the central finger to the other flanking finger, and a spring located in each of the outer cavities to return the respective fingers to their normal positions, the correlated spring conjointly returning the centrally positioned finger to its normal position wherein the stack is again restrained by the centrally positioned finger as the other flanking finger releases the bottom-most stud.

3. A pneumatically operated escapement for feeding one stud at a time from a magazine, comprising a body having a passageway therein forming a path along which the studs proceed in stacked relationship from the magazine, said body also having three cylindrical cavities therein whose respective axes intersect the axis of the passageway, three plungers each having a correlated finger associated therewith reciprocatingly disposed in the respective cavities, a spring biasing the centrally positioned finger to a normal position wherein it blocks the passageway thereby to restrain the stack of studs, the two outer cavities being located to position the two flanking fingers along the passageway on either side of the central finger at respective distances greater than the longitudinal length of one of the studs,

springs biasing the two flanking fingers respectively so that they are normally held clear of the passageway, and means for connecting said central cavity with an air supply to retract the centrally positioned finger to release the stack, said means subsequently moving the flanking fingers into their blocking positions wherein the stack is restrained by one of the flanking fingers as the bottom-most stud is transferred from the central finger to the other flanking finger, the disconnecting of the air supply permitting the springs to return the fingers to their normal positions wherein the stack is again restrained by the centrally positioned finger as the flanking finger releases the bottom-most stud.
